UNITED STATES PATENT OFFICE

HENRY D. POWNALL, OF CINCINNATI, OHIO.

COOLING AND CONDENSING APPARATUS.

SPECIFICATION forming part of Letters Patent No. 658,899, dated October 2, 1900.

Application filed December 7, 1899. Serial No. 739,492. (No model.)

To all whom it may concern:

Be it known that I, HENRY D. POWNALL, a citizen of the United States, residing at Cincinnati, in the county of Hamilton and State of Ohio, have invented certain new and useful Improvements in Cooling and Condensing Apparatus; and I do hereby declare the following to be a full, clear, and exact description of the invention, such as will enable others skilled in the art to which it appertains to make and use the same.

My invention relates to improvements in cooling and condensing mechanism.

One of the objects is to provide means whereby the impure sulfur and saline charged water of Artesian wells may be utilized for condenser and cooling purposes.

Another object is to prevent scale forming on the condenser-pipes.

Another object is to provide an improved non-corrosive heat-exchanging mechanism for the above purpose.

Another object is to provide a non-corrosive heat-exchanger which can be molded or built up in molds at a single operation.

Another object is to provide detachable heads of non-corrosive material.

Another object is to provide improved water-tight joints between non-corrosive parts for the purpose specified.

My invention also consists in the certain details and combination of parts, all of which will be fully described in connection with the accompanying drawings, in which—

Figure 1 is a vertical section through my improved heat-exchanger mechanism on line *y y*, Fig. 2. Fig. 2 is a horizontal section on line *x x*, Fig. 1. Fig. 3 is a perspective view of one of the stud-bolts for securing the heads in place. Fig. 4 is a section on line *z z*, Fig. 1. Fig. 5 is an inside plan view of the right-hand head, Fig. 1. Fig. 6 is an inside plan view of the left-hand head, Fig. 1. Fig. 7 is a detail sectional view of a modified joint or coupling for the pipes. Fig. 8 is a plan view of one of the pipe coupling-rings. Fig. 9 is a diagram of my improved condensing or cooling mechanism. Fig. 10 represents a modification of Fig. 1. Fig. 11 is a top plan view of Fig. 10 with head removed.

Great trouble has been experienced heretofore in employing deep-well water charged

with sulfurous compounds, sulfureted hydrogen, sulfurous oxid, salt, &c., for cooling and condensing purposes in ice-factories, distilleries, and breweries on account of the corrosive action of the sulfurous and saline compounds upon the pipes, tanks, framework, and all metal parts coming in contact therewith, necessitating the frequent replacing of the same. In my improved apparatus I overcome these difficulties and am enabled to use these waters as they come direct from the well for all ordinary cooling and condensing purposes, as shown in the accompanying drawings.

A, Fig. 9, represents the condenser-coils of an ice-machine or steam-condenser.

B represents a pump circulating pure water through pipe C over the coils A.

D represents a receptacle formed of stone or cement or a combination thereof, so as to be unaffected by the sulfurous water. Located within this receptacle and with their open ends projecting through the end walls *a* thereof are a series of tubes E, of glass, porcelain, gutta-percha, or other similar non-corrosive substance. Incasing the ends of these tubes are removable heads F F', provided with partitions *f*, which serve to direct the current of water successively through the several tubes E in tandem series.

G represents baffle-plates, causing the water in the receptacle D, surrounding the tubes, to travel in a circuitous route from the bottom 85 to the top thereof. This receptacle D is preferably formed at a single operation by molding a suitable composition of Portland or other cement and stone, sand, or gravel over cores containing the tubes, so that when the core 90 is removed the tubes are left firmly embedded in the cement of the end sections of the receptacle. If preferred, however, the tubes may be subsequently inserted and made replaceable or detachable, as indicated in Fig. 95 7, in which 1 represents a metallic ring embedded in the composition of the end sections; 2 represents stud-bolts projecting therefrom; 3 represents a gland, and 4 represents a rubber packing-ring, which is compressed into 100 position around the end of the tube to form a water-tight joint.

The warm pure water after passing over the coils A is caught in the pan K and fed

through the pipe H to the tubes E of the receptacle, being directed by the heads, as indicated by arrows in Figs. 1 and 2, so as to successively traverse the several tubes and 5 emerge through the pipe C, from whence it is circulated by the pump B over the coils A. The cold sulfurous water enters the receptacle D through the pipe I near the bottom and rises in a circuitous path, as indicated 10 by arrows, surrounds the tubes E, and cools the water circulating therein without coming in contact therewith and escaping through pipe N. By using distilled or other pure water I wholly obviate the difficulty of forming scale upon the condenser-coils, which is 15 one of the greatest difficulties experienced in the use of condensers, and at the same time secure the requisite quantity of condensing-water at approximately the same temperature 20 as that of the impure deep-well water.

In order to strengthen the heads F F', which 25 are preferably molded from a composition in the same manner that the receptacle is formed, I embed a perforated metal plate L in the material of the head. 5 represents eye-bolts to assist in removing and replacing the head. The heads are secured in place by means of stud-bolts 6, which are screwed into cast-metal bosses 7, anchored in the body of 30 the receptacle.

In the modification shown in Figs. 10 and 35 11 the sulfureted water enters through pipe I' and escapes through pipe N', while the pure water enters the chamber 8 beneath the head 9 and passes from thence through the several tubes simultaneously or in multiple series to the chamber 10, from whence it emerges cooled and passes to the condenser-coils.

40 d d' represent removable sections to permit access to the interior of the receptacle D. g represents passages for the water, cored in the body and heads of the receptacle.

Having described my invention, what I 45 claim is—

1. In a cooling and condensing apparatus, a coil of pipes in which the medium to be cooled or condensed is circulated, a non-corrosive receptacle through which the impure

cooling-water is circulated; a series of non-corrosive tubes spanning said receptacle; a body of pure water; and means for circulating it first through the tubes of the receptacle, where it is cooled, and then in contact with the condenser-coils, substantially as 55 specified.

2. In a cooling and condensing apparatus a coil of pipes in which the medium to be condensed is circulated; a non-corrosive receptacle through which the impure cooling-water is circulated, a series of non-corrosive tubes spanning said receptacle; removable heads inclosing the ends of said tubes; a body of pure water and means for circulating it first through the tubes of the receptacle, 60 where it is cooled and then in contact with the condenser-coils, substantially as specified.

3. As a new article of manufacture a cooling and condensing apparatus consisting of a receptacle molded from cement or other 70 vitreous composition; tubes of vitreous material spanning the same; heads with recesses forming connecting-passages between the tubes, metal studs bedded in the composition for securing and holding the heads in 75 place; and outside pipe connections directing the different mediums respectively to the inside and outside of said tubes, substantially as specified.

4. In a cooling and condensing apparatus, 80 a receptacle molded in a single piece from cement or other similar vitreous material; a series of tubes of vitreous material spanning the same; removable heads incasing the ends of said receptacle and provided with recesses 85 forming connecting-passages between the pipes; means substantially as described for detachably securing the heads in place; and outside pipe connections directing the different mediums respectively to the inside and 90 outside of said tubes, substantially as specified.

In testimony whereof I have affixed my signature in presence of two witnesses.

HENRY D. POWNALL.
